United States Patent Office

Des. 202,188
Patented Sept. 7, 1965

202,188

CABINET FOR HIGH VACUUM STATION

Monte L. Levin, Roslyn Heights, N.Y., assignor to
Vacuum-Electronics Corp.

Filed Apr. 16, 1964, Ser. No. 79,526

Term of patent 14 years

(Cl. D26—5)

FIG. 1

FIG. 2

FIG. 3

FIG. 4

FIG. 1 is a perspective view of a cabinet for high vacuum station showing my new design;

FIG. 2 is a top plan view thereof;

FIG. 3 is an end elevational view thereof; and

FIG. 4 is a rear elevational view thereof.

The side not shown is the same in appearance as the side shown.

I claim:

The ornamental design for a cabinet for high vacuum station, substantially as shown and described.
